B. Hinkley,
Thrashing Mach.

Patented July 23, 1833.

Drawing No. 3

The Improved Reaping

Scarecrow.

The Scarecrow referred to in the last Patent & making part of the same
continuing description in the body of the said Benjamin Binkley
(himself of his improvement in the threshing Machine).

This machine is intended to be operated by hand or with power, and
the size and dimensions will vary according to its being operated in the
timber, or the dimensions suitable for hand power are four feet high,
three inches square, rails for ends are 18 inches long and four inches wide & two
inches thick, the side rails are three feet long, one foot wide and two
inches thick. The front end rail is dropped to within three inches
of the bottom of the posts. The back end rail is raised to within three inches
of the top. The side rails and the frame is put together with screws or
bolts and in putting the frame together the side rails must be formed
in even with the middle of the posts. These rails are represented on the
drawing referred to in this description and making a part of the same, are
marked C. The posts are marked A. Fig. A of the drawing
represents the large cylinder filled with rods of pitch or iron projecting
about a fourth of an inch ^{and may be one eighth of an inch} in the ends. The teeth in the rods are within
half an inch of each other. Fig. C. of the drawing represents a slow
wheel four inches in diameter above end of the cylinder, on the opposite
end of the cylinder is a spur wheel ground for a round hand of wood
one inch, and on the same end is a balance wheel to regulate the motion
three feet in diameter. Fig. B represents the balance wheel and fig. C.
the spur wheel. Under the cylinder and fitted to work with it is a short
mnogated arm. First of plain steel of two pieces of one inch apart
four inches wide laying upon wooden springs. The quota is of thick steel
iron furnished full upon all sides and attached to the wooden bridge as
by riveting the plain edges to the upper part of the two pieces. At the upper
edge of the two pieces is a piece of flat iron with four teeth filed in, project-
ing about one half inch. Fig. D a diagram of a long narrow wheel
spoked on one side and made into a wheel C. when in use

farther from the door than the smaller cylinder (one inch in diameter &) the length of the larger cylinder, and to the end of this shaft is attached the comb or combinator by the turning. Fig. D represents the comb or cleaver, which is made of a piece of wood two inches square, two feet long, in this case placed lengthwise, known then the comb is projecting about one inch, a small iron guard in each end, on one end and off is a small wheel two inches in diameter, which receives the band and is driven by the fly-wheel. The comb is placed by two arms ^{one} to meet the the large cylinder as can be without cutting. Fig. E represents two teeth let into the top of the post. Fig. F is a platform on which to lay the grain. Fig. G is an apron fastening on one side of the post for the horses and receives the grain which is carried in by the teeth. What I claim as new and of my own invention is the greater arm resting on springs and applied to the cylinder in the manner described. The form and disposition of the teeth in the cylinder. the comb or cleaver to throw off the straw.

And witness, John C. H. John C. H. John P. Hagg.

Benjamin Brinkley.
